(57) **CLAIM**

I claim the ornamental design for a lid and seal for container, as shown and described.

DESCRIPTION

FIG. 1 is a front perspective view, from above, of the claimed design;

FIG. 2 is a rear perspective view, from beneath, of the claimed design;

FIG. 3 is an exploded front perspective view, from above, of the claimed design, showing the lid component and seal component separated;

FIG. 4 is an exploded rear perspective view, from beneath, of the claimed design, showing the lid component and seal component separated;

FIG. 5 is a side view of the claimed design, showing the lid component and seal component in combination (when connected together);

FIG. 6 is a top plan view of the lid component of the claimed design;

FIG. 7 is an end plan view of the claimed design, showing the lid component and seal component in combination (when connected together);

FIG. 8 is an underneath plan view of the claimed design;

FIG. 9 is a side view of the lid component of the claimed design. Both side views are the same;

FIG. 10 is an end view of the lid component of the claimed design. Both end views are the same;

FIG. 11 is an underneath view of the lid component of the claimed design;

FIG. 12 is a side view of the seal component of the claimed design. Both side views are the same;

FIG. 13 is a top view of the seal component of the claimed design;

FIG. 14 is an end view of the seal component of the claimed design. Both end views are the same; and,

FIG. 15 is a bottom view of the seal component of the claimed design.

The purpose of broken lines in the drawings is to illustrate an optional vent that forms no part of the design to be patented.
